(57) **CLAIM**

The ornamental design for a foldable basket, as shown and described.

DESCRIPTION

FIG. 1 is a front-right-top perspective view of a foldable basket showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a rear-right-bottom perspective view thereof;

FIG. 9 is a perspective view thereof, shown in a folding state; and,

FIG. 10 is another front-right-top perspective view; shown in a state of use.
The broken lines in FIG. 10 showing portions of a bike depict environmental subject matter that form not part of the claimed design.

1 Claim, 10 Drawing Sheets
